UNITED STATES PATENT OFFICE

JOHN E. WOODBURY, OF WORCESTER, MASSACHUSETTS

DOCTOR CLEANING DEVICE

Application filed March 27, 1931. Serial No. 525,824.

This invention relates to a doctor cleaning device for use in inking intaglio plates or dies for fine printing.

The principal objects of the invention are to provide simple means for cleaning both sides of the doctor while in substantially horizontal position over the printing plate, having accessible adjustments; to provide means without complicated linkages for cleaning the doctor after each inking operation so that the ink is not only cleaned from the operative side of the doctor but a body of ink will not be left on the opposite side of the doctor at the edge of the blade; to provide means, readily accessible for cleaning when the machine is not running, for engaging the two surfaces of the doctor and moving said engaging means backwardly, so that the two surfaces will be cleaned at the same time, and to provide means for raising the upper doctor cleaning blade combined with means for raising the doctor blade to allow for the back stroke without allowing the doctor blade to come into contact with either of the cleaning blades at that time, this also involves the provision of means for backing up the doctor blade while it is being cleaned on the surface which collects the ink from the printing plate.

Other objects and advantages of the invention will appear hereinafter.

Reference is to be had to the accompanying drawings, in which

Fig. 1 is a side view of a portion of an intaglio printing plate machine showing in full lines the position of the cleaning means while it is operating to clean the doctor and showing in dotted lines the cleaning means retracted fully;

Fig. 2 is an end view of the same as indicated by the arrow 2 in Fig. 1;

Fig. 3 is a sectional view on the line 3—3 of Fig. 1;

Fig. 4 is a horizontal sectional view on the line 4—4 of Fig. 3 and on enlarged scale;

Fig. 5 is an end view of the doctor operating cam;

Fig. 6 is a view similar to Fig. 1 showing the parts in the same position and illustrating the relationship between the plate and the doctor blade at this time;

Fig. 7 is a similar view showing the position of the parts while the plate is being inked;

Fig. 8 is a view of the doctor cleaning parts and showing the way of operating the upper doctor cleaning blade, and

Fig. 9 is a similar side view showing the motion of the doctor cleaning blade in dotted lines after the cleaning of the plate is completed.

The invention is shown as applied to a machine for printing from an intaglio plate. This plate is fixed to a table 11 which reciprocates, as the arrows indicate in the several figures, horizontally. The means for operating this plate is not shown as the invention is intended to apply to practically all types of machines in which the table for supporting an intaglio printing plate is reciprocated.

The plate is inked by a roller 12 mounted on an oscillating arm 13 as is well known in this industry, and this ink roller 12 gets its ink from a fountain roll 14 mounted in an ink fountain 15. These parts are all well known and no particular construction of the operating means therefor is illustrated herein.

The doctor blade 16 is mounted on an oscillating shaft 17 and the position which it occupies when cleaning the plate is indicated in full lines in Fig. 9, the plate 10 passing under it and the surplus ink being cleaned off by the doctor blade, leaving the ink in various indentations of the plate for printing. After this plate passes by the doctor

blade, the blade is lifted to the dotted line position in this figure and also in Fig. 8.

The mechanism for operating this doctor blade comprises a shaft 20 operated, by means not shown, in synchronism with the press. On that shaft is a cam 21 which is provided with cam plates 22 provided with slots and secured to the cam itself by bolts 23, so that the depressed part 24 of the cam can be regulated in length. On this cam rests a roll 25 on a lever 26 connected with an arm 27 by an adjusting screw 28. The high part of the cam 21 forces the doctor blade up to the dotted line position in Figs. 8 and 9, and the low part of the cam or space 24 allows the doctor blade to drop down on the plate. A spring 30 is employed to hold it down on the plate with yielding pressure, so that it will act effectively to clean the plate. An adjustable stop 19 is provided for the arm 27 on the shaft 17 to limit the pressure with which the spring 30 can force the blade against the plate.

On a shaft 20 is a gear 31 meshing with a gear 32 on a shaft 33. The shaft 20 is operated from the press in synchronism with the motion of the table 11. The connections therefor are not shown herein, as any desired system of gearing can be used, and in ordinary types the shaft is a shaft which already exists in the press or it can be geared to some such shaft in a simple manner to secure this result in proper timing.

On the shaft 33 is a cam 34 which operates a cam roll 35 on a lever 36. This lever is provided with an adjusting screw 37 which controls the motion of the lever of a bell-crank 38, and a spring 39 keeps one arm of this bell-crank against this adjusting screw. The other arm of the lever 38, which is pivoted on a rod 40, engages a roll 41 on an arm 42 pivoted on a shaft 43 when these parts are brought up to this point. This shaft carries the upper doctor cleaning blade 44. The rising of the roll 35 causes a depression of the roll 41 and the raising of the blade 44, as shown in dotted lines in Fig. 8. This shaft 43 is mounted on brackets 46 which carry an ink receptacle 47 which also reciprocates, of course. This ink receptacle also carries fixed thereto the lower cleaning blade 48. The motion of this lower cleaning blade is exactly horizontal, and its upper surface is in a position to clean the doctor blade, when that is in exactly horizontal position as shown in Fig. 6. By "horizontal" I mean parallel with the path of motion. This path of course might be inclined or even vertical.

The gear 31 also meshes with a gear 50 which is provided with an eccentric stud 51 operating a link 52 pivoted to an arm 53 fixed to an oscillatable shaft 54. The motion of the stud 51 therefore operates this shaft 54. On this shaft 54 is fixed an arm 55 which is pro-

vided with a pin 56 that enters a notch in a head 57. This head 57 is fixed on the doctor blade shaft 17. Obviously the vibration of the shaft 54 vibrates the doctor blade longitudinally as is usual. It may be stated here that the adjusting screw 19 which controls the pressure between the doctor blade and the plate is mounted on the frame. The head 57 has surfaces on its arm 27 adapted to be engaged by this stud and also the stud 28 and the spring 30.

In operation, the plate in its forward or printing position, shown in Fig. 1, remains at rest for a large portion of a cycle of operations while the print is being made. This may be as much as 135° out of 360° . Before the plate reaches this forward position the doctor rises slightly above the normal horizontal position by the action of the cam 21 and the upper doctor cleaner blade 44 is lifted above its normal position, as shown in dotted lines in Fig. 8, in the manner that has been described. This action makes possible the progress forward of the lower blade 48 of the cleaner unit without interfering with the doctor. This lower blade, of course, is fixed with respect to the table 11 and moves with it and also the ink receptacle 47 always moves with it.

When the plate 10 has reached the position shown in Fig. 1 and the cleaning mechanism is also in that position the cam 21 comes to a position to rotate the shaft 17 slightly so that the doctor blade assumes a horizontal position in position to contact with the doctor cleaner blade 48. At the same time the cam 34 moves the lever 38 upwardly so that the upper cleaner blade 44 comes into contact with the top of the doctor blade. This is shown in Fig. 6.

At the end of the 135° of rest in Fig. 1 position, the plate goes back into the position shown in Fig. 7 at the extreme rear. It passes under the ink roller both going back and coming forward. On the forward stroke, when the plate reaches the edge of the doctor blade, this blade is lowered against the plate as indicated in Fig. 9 and scrapes the surplus ink off. As the plate reaches a point where the doctor is at the rear end of it, the doctor is slowly raised, first to horizontal position, and then above it to clear the blade 48 as stated.

The ink is wiped from the doctor at each cycle by the lower and upper blades and runs down the surface of the blade 48 into the ink receptacle 47. This ink, of course, is salvaged.

This machine has many advantages. It is perfectly simple, being free from complicated link motions, the cleaner unit is absolutely accessible for being cleaned while the machine is not running and it can be cleaned every night or every week-end. The doctor

is moved only slightly. The adjustments are all accessible and of the simplest character.

Although I have illustrated and described only one form of the invention I am aware of the fact that modifications can be made there-in by any person skilled in the art without departing from the scope of the invention as expressed in the claims. Therefore I do not wish to be limited in this respect, but what I do claim is:—

1. The combination with a doctor for removing the ink from a printing plate, of means for moving the doctor to a horizontal position and means relatively movable along the doctor horizontally on both sides thereof for cleaning the ink therefrom.

2. In an intaglio printing press, the combination with means for holding a printing plate with its printing side up and reciprocating it horizontally, of an inking roll in position to apply ink to the face of the plate, a doctor for cleaning the surplus ink off the die and means movable with the plate for removing the ink from the surfaces of the doctor as the plate moves back from printing position.

3. In an inking device, the combination with means for inking a printing plate located with its engraved side up, of a doctor in position for removing the surplus ink from the plate and means for engaging both the upper and lower surfaces of the doctor and removing the ink therefrom as the plate moves back.

4. In an inking device, the combination with means for inking a printing plate located with its engraved side up, of a doctor in position for removing the surplus ink from the plate and means for engaging the rear surface of the doctor and removing the ink therefrom as the plate moves back.

5. In an inking device, the combination with a doctor adapted to remove the ink from a printing plate, and means for moving the doctor to a horizontal position, of a scraper blade, means for moving the scraper blade downwardly to a point to engage the upper surface of the doctor, and means for then moving the scraping blade along the doctor toward the edge thereof.

6. The combination with a reciprocating table for holding an engraved printing die or plate with its face up and means for inking the upper surface of the printing plate, of a doctor, means for turning the doctor into contact with the plate for removing the surplus ink, means for raising the doctor out of contact with the plate after the printing operation, means for turning the doctor, a scraper blade over the doctor for removing the ink from the doctor, means for moving said scraper blade to bring it into contact with the doctor, and means for moving the scraper along the surface of the doctor to scrape the ink off the upper surface thereof.

7. The combination with a reciprocating table for holding an engraved printing die or plate with its face up and means for inking the upper surface of the printing plate, of a doctor, a shaft on which said doctor is fixed, means for turning said shaft slightly to bring the doctor into contact with the plate for removing the surplus ink, means for raising the doctor out of contact with the plate after the printing operation, means for turning the shaft to a position in which the doctor extends horizontally, a scraper blade over the doctor for removing the ink from the doctor, means for moving said scraper blade to bring it into contact with the doctor and means for moving the scraper along the surface of the doctor to scrape the ink off the upper surface thereof.

8. The combination with a reciprocating table for holding an engraved printing die or plate with its face up and means for inking the upper surface of the printing plate, of a doctor, means for turning the doctor into contact with the plate for removing the surplus ink, means for raising the doctor out of contact with the plate after the printing operation, means for turning the doctor, a scraper blade over the doctor for removing the ink from the doctor, means for moving said scraper blade to bring it into contact with the doctor, means for moving the scraper along the surface of the doctor to scrape the ink off the upper surface thereof, and a second blade under the doctor always in registration with the first named scraping blade to back up the doctor at that point and prevent ink from remaining on the under side of the doctor.

9. The combination with a doctor for scraping the surplus ink from the face of an intaglio printing plate or die, a shaft on which the doctor is fixed, means for vibrating said shaft in an axial direction constantly while it is in operation for removing the ink from the plate, means for turning the shaft to bring the doctor into a horizontal position, a scraper blade for cleaning the ink from the upper surface of the doctor, a frame on which the scraper blade is carried, said frame being pivoted on an axis, and means for raising said frame with the scraper blade in an arcuate path to bring the edge of the scraper blade away from the doctor to allow the doctor to pass under it.

10. In an intaglio plate printing machine, the combination with a table reciprocable in a plane and carrying the printing plate, of a doctor blade for the printing plate and means for scraping the opposite surfaces of the doctor blade connected with said table to move exactly with it.

11. In an intaglio plate printing machine, the combination with a table reciprocable in a plane and carrying the printing plate, of a doctor blade for the printing plate and

means for scraping the lower surface of the doctor blade connected with said table to move exactly with it, means for swinging the doctor blade through a slight angle to an inclined position over the plate to remove the surplus ink therefrom and then to a horizontal position over the cleaning blade and to an upwardly inclined position to allow the lower cleaning blade to come under it.

10 In testimony whereof I have hereunto affixed my signature,

JOHN E. WOODBURY.
